UNITED STATES PATENT OFFICE.

BENGT M. W. HANSON, OF HARTFORD, CONNECTICUT, ASSIGNOR TO PRATT & WHITNEY COMPANY, OF HARTFORD, CONNECTICUT, A CORPORATION OF NEW JERSEY.

STEADY-REST FOR METAL-REDUCING MACHINES.

No. 905,521.

Specification of Letters Patent.

Patented Dec. 1, 1908.

Application filed May 31, 1907. Serial No. 276,649.

To all whom it may concern:

Be it known that I, BENGT M. W. HANSON, a citizen of Sweden, residing at Hartford, in the county of Hartford and State of Connecticut, have invented certain new and useful Improvements in Steady-Rests for Metal-Reducing Machines, of which the following is a specification.

This invention has reference to reducing-machines and especially machines of that character relating to the reduction of metal by a grinding-operation.

The primary object of the invention is to provide in combination with a steady-rest support or carrier preferably mounted for movement in a straight path, means of a simple and effective nature for advancing said support or carrier and for unyieldingly preventing retractive or backward movement of said support or carrier by reason of which extreme accuracy of work is possible.

Other objects of the invention will be hereinafter stated.

In the accompanying drawings, Figure 1 is a side elevation of devices showing one form of my invention; and Fig. 2 is an end view of said devices.

Like numerals designate similar parts throughout the several views.

Referring to the drawings, the numeral 1 designates a slide on the carriage of the machine (not shown), and clamped in place adjustably on said carriage by means designated in a general way by 2, and to which no claim of invention is made in the present case. Adjustably fitted in the top of the slide 1 is another slide 3, which acts as a support for the devices to be hereinafter described, and depending from this slide 3 is an extension 4 bearing against a spring-actuated plunger 5 fitted in a bore of said slide 1. A screw 6 is in a bore of the slide 1, and a thumb-nut 7 engages said screw, and permits a free adjustment of said slide 3 to be made, the hub of said thumb-nut bearing against a projection 4 on said slide 3.

Rising from the slide 3 is a standard 8, and secured to said standard by screws 9 is a vertical support 10 having an inclined arm 11. Pivoted at 12 to the vertical support is an arm or lever 13 grooved as shown in dotted lines at 14 to receive a roller 15. Fitted in grooves of said inclined arm 13 is a weight 16 adjustably secured at any point

along the bottom of the arm by a screw 17 or in any other desired manner. At the inner end arm 14 is provided with a nose or shoulder 18 and projecting from the slide or support 3 is an elongated bolt or stud 19. A boss 20 is formed integral with the support 10, and secured by a pin 21 in a seat of said boss is a bolt 22 having a threaded section 23, and a nut 24 upon said threaded section. Sleeved on the bolt 19 is a support or bracket 25 and rigid with said bracket is an arm 26 through which the bolt 22 passes. A screw 27 having a thumb-nut 28 is threaded into the support or bracket 25, and said screw has a tip 29 bearing against the end of the nose 18 or projection 18 of the arm 13. On the inner side of the support or bracket 25 is located a shoulder 30, and said support or bracket also carries a nose or projection 31 for engaging an arm 32 projecting from a steady-rest 33 provided with a preferably integral shoe 34, and with angular studs 35. This steady-rest 33 is located at an angle preferably about forty-five degrees to the axis of the work 36 under process of reduction, said work being supported by the usual centers. (Not shown).

In the operation of the machine the carriage thereof is moved back and forth to cause the grinding-wheel or other reducing agent to operate upon the work, and as said work is reduced it is important to hold the shoe of the steady-rest against the same under positive and unyielding pressure and to prevent any back action of said steady-rest which would permit it to leave the surface of the work. In the present instance this is accomplished in the following manner:—As will be observed the support or bracket 25 is slideable upon and guided by the rod or bolt 19, and is limited in its sliding movement by the nut 24, said rod or bolt constituting a convenient and simple relatively fixed guide means for the steady-rest support or carrier. To cause this sliding movement of the support 25 the nose of the bar 13 will, under the influence of the roller 15 sliding in a groove 14 of said bar 13, co-acting with the incline 11 on arm 11, and under the influence of adjustable weight 16 cause said nose 18 to bear against the tip of the screw 27 and thereby automatically force the shoe 34 of steady-rest 33 to keep in contact with the work being reduced and to follow up the reduction of said work.

- Stress of the work in revolving against the shoe is counteracted by the nose 31 in engagement with the arm 32 of said steady-rest, thereby preventing the lifting of the 5 angular studs 35 from their seats in the bifurcated support 25 as will be readily understood. A limit to the reduction of the work is provided for by the adjustable nut 24. It will, therefore, be seen that the shoe 10 34 will follow up the reduction of the work by positive and unyielding mechanical means, and that any vertical adjustment required of said shoe may be obtained by the screw 27, the top of which is in contact with 15 the nose 18, and preferably the slot 37 in the slide 3 is in the shape of a T-slot to receive a T-head 38 projecting from the support 1, as shown by dotted lines in Figs. 1 and 2.
- 15 20 By the means described the shoe 34 engages the work under positive and unyielding action and is kept in contact therewith automatically by the arm 18, the rolling weight 15 and the inclined arm 11 secured 25 to the standard 8 of the slide.
- Changes may be made in the various details of the invention without departure therefrom, said invention not being limited to the precise devices illustrated and described, but includes within its purview means broadly for holding the steady-rest against the work under positive and unyielding pressure.
- Having thus described the invention, what 30 I claim is:
1. The combination of a steady-rest support mounted for movement in a straight path, and means for automatically advancing said support and for unyieldingly preventing retractive movement thereof.
  2. The combination of a steady-rest support mounted for movement in a straight path, a lever active against said support for advancing the same, and means including a 45 bodily movable device for unyieldingly preventing retractive movement of said support, said bodily-movable device being operable against the lever.
  3. The combination of a steady-rest support mounted for movement in a straight path, a lever active against said support for advancing the same, a fixed element, and a bodily-movable device located between said fixed element and lever and operable against 55 the latter to prevent unyieldingly retractive movement of said lever.
  4. The combination, with a support, of a device carried thereby for engaging the work, and unyieldable with relation to said work; a mechanical device for forcing said support toward the work under unyielding pressure; and means for returning the support on the completion of the reducing operation.

5. The combination, with a support, of a device carried thereby for engaging the work, and unyieldable with relation to said work; a mechanical device for forcing said support toward the work under unyielding pressure; a stop for limiting the forward 70 action of said support; and means for returning the support on the completion of the reducing operation.

6. The combination, with a support, and with a device rigidly mounted thereon for 75 engaging the work, of means for advancing said support under unyielding pressure, and an adjustable stop for limiting the movement of said support.

7. The combination, with a support, and with a device rigidly mounted thereon for engaging the work, of means for advancing said support under unyielding pressure, and an adjustable stop for limiting the movement of said support; and a spring for returning the support.

8. The combination, with a bodily movable support, of a device movably mounted thereon, and rigid therewith for engaging the work, said device having a shoe shaped 90 to conform to said work, and said device being located at an angle to the work, and means for positively and automatically advancing the support to follow up the reduction of said work.

9. The combination, with a support, of a device movably mounted thereon, and rigid therewith for engaging the work, said device having a shoe shaped to conform to said work, and said device being located at 100 an angle to the work, means for positively and automatically advancing the support to follow up the reduction of said work; and a stop for limiting the forward movement of said device.

10. The combination of a bodily-movable steady-rest support, stationary guiding means for said support, and means for automatically advancing said support and for also unyieldingly preventing retractive movement 110 thereof.

11. The combination of a steady-rest support mounted for movement along a straight path, a relatively fixed rod for guiding said support, and means for automatically advancing said steady-rest support and for also unyieldingly preventing retractive movement thereof.

12. The combination of a steady-rest support, a screw adjustably carried by said support, and means acting against the screw for advancing the support and for also unyieldingly preventing retractive movement thereof.

13. The combination of a steady-rest support, a screw adjustably carried by said support, means acting against the screw to advance the support and for also unyield-

ingly preventing retractive movement of said support, and a second screw for limiting the advancing movement of said support.

14. The combination of a support movable along a straight path, a device rigid on said support for engaging the work and having a portion shaped to conform to such work, and means for automatically advancing the

support and for also unyieldingly preventing retractive movement thereof. 10

In testimony whereof I affix my signature in presence of two witnesses.

BENGT M. W. HANSON.
